UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,407,289.

Specification of Letters Patent. Patented Feb. 21, 1922.

Application filed November 4, 1920. Serial No. 421,676.

To all whom it may concern:

Be it known that I, RONALD A. McCANN, a citizen of the United States, residing at Swissvale, in the county of Allegheny and 5 State of Pennsylvania, have invented certain new and useful Improvements in Railway-Traffic-Controlling Apparatus, of which the following is a specification.

My invention relates to railway traffic 10 controlling apparatus, and particularly to apparatus of the type comprising signals which are controlled, at least in part, by manually operable devices such as levers of an interlocking machine. More specifically, 15 my invention relates to apparatus of this character comprising signals which have two blades or arms known as the main arm and the "calling-on" arm.

I will describe certain forms of apparatus 20 embodying my invention, and will then point out the novel features thereof in claims.

In the accompanying drawings, Fig. 1 is 25 a view, largely diagrammatic, showing one form of apparatus embodying my invention, and Fig. 2 is a view similar to Fig. 1 but showing a modified form of apparatus also embodying my invention.

Similar reference characters refer to similar parts in each of the views.

Referring first to Fig. 1, the reference characters 2 and 2^a designate the two rails of a railway track R over which traffic normally moves in the direction indicated by the 35 arrow. These rails are divided by insulated joints 3 to form a stretch of track A—H, which I will call the interlocking block, and a preliminary or approach section H—C. The block A—H may comprise any desired 40 number of insulated track sections, only one such section being shown in the drawing to simplify the disclosure. This section is provided with a track circuit comprising a track battery b and a track relay T, and the approach section is similarly provided with a track circuit comprising a battery b' and a track relay T'.

Traffic into the block A—H is governed 50 by a signal S comprising a high or main arm 4, and an auxiliary or "calling-on" arm 5. Each of these arms normally occupies a horizontal position as shown in the drawing, wherein it indicates "stop," but each arm may be moved to an inclined position where-

in it indicates "proceed," the main arm when 55 in such position giving a high speed indication and the calling-on arm a low speed indication or a warning that the block A—H is probably occupied. The manner in which signal S is controlled will be explained in detail hereinafter.

The approach section H—C is provided with a signal S' which is controlled jointly by track relay T' and by arm 4 of signal S, so that this signal indicates "stop" when section H—C is occupied, "caution" when such section is unoccupied and arm 4 is at "stop," and "proceed" when section H—C is unoccupied and arm 4 is in the proceed position. The controlling apparatus and circuits for signal S' conform with standard and well understood practice, and form no part of my invention, and hence they are omitted from the drawing to simplify the disclosure as far as possible.

Track relay T' controls a relay D which is known as an "approach locking relay," the control being such that relay D is closed or open according as relay T' is closed or open. The circuit for relay D is from the terminal B of a suitable source of current, through contact 6 of relay T', wire 7, winding of relay D, to terminal O of the same source of current.

Signal S is controlled jointly by track relay T for the stretch of track A—H, and by a manually operable lever L. The lever L is one of a plurality of levers in an interlocking machine, which levers govern various switches, signals, etc., controlling traffic 85 through the block A—H. This lever, in the form here shown, is mounted to swing on its longitudinal axis, and is provided with a handle 8 to facilitate manual operation. The lever normally occupies a position 90 wherein the handle is vertical, and when in such position both arms of signal S are at stop; the lever may be swung from its normal position to clear arm 4 or 5, according to traffic conditions within the block A—H 100 as will hereinafter appear, and in actual practice it usually may also swing to the right to clear another signal which governs traffic moving towards the right through block A—H but which is not shown in the 105 drawing.

The lever L is controlled by an indication device or lock comprising a segment 9 at-

tached to the lever and provided with a dog 10. Coacting with this dog is a latch 11 having at its upper end a horizontal jaw which rests on the dog when the lever is in 5 the normal or middle position. When the lever is swung in one direction or the other, however, the latch falls by gravity into the path of the dog 10, so that the lever can then be returned only part way to its 10 normal position, that is, to a right hand or a left hand indicating position. The lever can be returned to its full normal position only after a magnet 12 has been energized to attract its armature 11^a and so to raise 15 latch 11 out of the path of dog 10.

The reference character E designates an "automatic release relay" which is controlled jointly by track relay T and lever L. This relay is provided with a pick-up circuit 20 which passes from terminal B² of a suitable source of current, through contact 13 of track relay T, wire 14, winding of relay E, wires 15 and 16, and contact 17 on lever L to terminal O² of the same source of current. Contact 17 is closed when lever L is in its middle or normal position, but is opened as soon as this lever is moved toward the left. It follows that when relay E is de-energized it can become energized only 25 if track relay T is closed and lever L is in the normal position. Track relay T is closed only when the block A—H is unoccupied. If this block comprises more than one track circuit, then, in accordance with 30 usual practice, the pick-up circuit for relay E will include a contact of each track relay in the block, these contacts being included in series in the circuit for relay E. Relay E is provided with a holding circuit which 35 passes from terminal B², through contact 13 of track relay T, wire 14, winding of relay E, wires 15 and 18, contact 19 of relay E, to terminal O³ of the same source of current. It follows that after relay E once becomes 40 energized, it will remain energized even though lever L be subsequently swung to the left, but will become de-energized as soon as a train enters the block A—H.

The main arm 4 of signal S is provided 45 with a circuit which is controlled jointly by the automatic release relay E and by lever L. This circuit passes from terminal B¹ of a suitable source of current, through contact 20 of lever L, wire 21, contact 22 of 50 relay E, wire 23, operating mechanism for signal arm 4, and wire 24 to terminal O¹ of the same source of current. Contact 20 is closed only when lever L is swung to the full left hand position. It follows that 55 when the block A—H is unoccupied, the operator may cause the main arm 4 of signal S to move to the proceed or clear position by swinging lever L to the extreme left. The lever L cannot, thereafter, be returned 60 to its full normal position until magnet 12

is energized, although it may be returned at any time to its left hand indicating position wherein contact 20 is open, so that arm 4 of signal S returns to its stop position.

I will now assume that the main arm 4 of signal S has been cleared and that a train has entered the block A—H. This train, of course, opens track relay T, which in turn de-energizes relay E, thereby opening the circuit for arm 4 at contact 22, so that this 70 arm returns to the stop position. Magnet 12 then becomes energized by virtue of a circuit which passes from terminal B³ of a suitable source of current, through contact 25 operated by signal S', and closed when 75 this signal is in the stop or caution position, wire 26, contact 27 operated by signal arm 5, and closed only when such arm is in the stop position, wire 28, contact 29 operated by signal arm 4 and closed only when such 80 arm is in the stop position, wires 30 and 31, back contact 32 of relay E, wire 33, contact 34 operated in the manner hereinafter explained, wires 35 and 35^a, contact 36 operated by lever L, wire 37, and magnet winding 12, 90 to terminal O³ of the same source of current. Contact 36 is closed when lever L is in the extreme left hand position or in the left hand indicating position, or at any point between these two positions. The circuit just traced 95 is what is known as the "automatic release circuit," and it will be seen that when it is closed, it permits the operator to return lever L to the normal position, thereby releasing other levers which control routes conflicting 100 with the route governed by signal S.

It is sometimes necessary to return lever L to the normal position after arm 4 has been cleared and before a train has entered the block A—H. If there is no train in the approach section H—C, the lever may be released by what is known as the "approach locking circuit." To do this the lever is first returned to its left hand indicating position, thereby placing signal arm 4 in the 110 stop position and returning signal S' to the caution position. Magnet 12 is then energized by virtue of a circuit which passes from terminal B³, through contact 25, wire 26, contact 27, wire 28, contact 29, wires 30, 38 and 115 39, contact 40 of approach locking relay D, wires 41, 42, 35^a, contact 36, wire 37, and magnet winding 12, to terminal O³ of the same source of current. This circuit is what 120 is known as the "approach locking circuit," and it permits the return of lever L to the normal position before a train has entered section H—C.

It is also sometimes necessary to return lever L to the normal position while a train 125 occupies the approach section H—C, and to permit this the approach locking circuit for magnet 12 is provided with a time controlled hand release F. This release comprises a contact which is normally opened, 130

but which may be closed by a manual operation requiring a predetermined period of time. This period of time is greater than the time required for a train moving at normal speed to pass through the approach section H—C. When the contact of the release F is closed, it closes a branch around contact 40 of relay D, which branch passes from wire 38 through wire 43, the contact of the release 10 F, and wire 44 to wire 42. It follows, therefore, that even though relay D is open, due to the presence of a train in section H—C, the release magnet 12 may be energized to permit lever L to be returned to its middle 15 position.

As stated hereinbefore, the lever L is one of a plurality of similar levers in an interlocking machine, some of which levers control switches and others of which control 20 signals. When lever L is in its extreme left hand position, or in its extreme left hand indicating position, it locks in normal position all other levers governing routes which in any way conflict with the route governed by 25 signal S. It is essential, therefore, that the means hereinbefore described should be provided for preventing the return of lever L to its full normal position, except under predetermined conditions.

30 I will now assume that while the block A—H is occupied by the train which has been admitted in the manner hereinbefore explained, the operator desires to permit a second train moving in the same direction to 35 enter this block. To do this, he leaves lever L in the left hand position, or returns it to such position if it has been restored to normal position, and then presses a pushbutton P inwardly. This operation of the pushbutton 40 closes a contact 45 and opens contact 34. The closing of contact 45 closes a circuit for the calling-on arm 5, which circuit is from terminal B⁴ of a suitable source of current, through contact 45, wire 46, contact 45, 47 on lever L, wire 48, contact 49 operated by main arm 4 and closed only when this arm is in stop position, wire 50, operating mechanism for arm 5, and wire 24 to terminal O' of the same source of current. Signal 45 50 arm 5 then moves to the proceed position, thereby advising the engineer of a following train that he may enter the block A—H at 55 low speed, expecting to find the block occupied.

Push-button P is so located in the interlocking machine that it is directly behind handle 8 when lever L is in normal position. It follows, therefore, that this button can be operated only when the lever has been swung 60 to the left or to the right. This button is, furthermore, controlled in the following manner. The shank p^a of the button is provided with a shoulder 51, and a dog 52 is pressed upwardly against this shoulder by a 65 spring 53. When the button is pushed in,

the dog 52 rises, under the influence of the spring, into locking position at the left end of shoulder 51, and so locks the button in the operated position. To release the button, the dog 52 is provided with a tappet 54 the 70 lower end of which straddles the button shank and is attached to the dog, and the upper end of which carries a roller 54^a coacting with a cam 55 fixed to the shaft of lever L. This cam is so shaped that the tappet 75 exerts no influence on dog 52 when lever L is in either extreme position or either indicating position, but that when the lever is restored to the full normal position the tappet is driven downwardly to push the dog 80 out of the path of shoulder 51, whereupon the push button returns to the normal position under the influence of a spring 56.

It will be seen from the foregoing that when button P has once been operated, it 85 cannot be restored until lever L has been returned to the normal position. But when the button P is in the operated position, contact 34 is open so that the automatic means for releasing lever L is ineffective, that is, 90 the circuit branch through back contact 32 of relay E cannot be used to energize magnet 12. The fact that relay E is open due to the presence of the first train in block 95 A—H does not, then, permit lever L to be released by the automatic means, but on the other hand this lever can be released only by the approach locking means or by the slow-acting hand release F. In other words, 100 when the calling-on arm 5 has been cleared, lever L cannot be released to permit a conflicting route to be set up after a train has passed signal S', except by operation of release F, the time element of which is, of course, greater than the time normally consumed by a train in passing through approach section H—C.

Referring now to Fig. 2, the circuit for the control of the main arm 4 of signal S is the same as in Fig. 1. The circuits for the 110 release of lever L after this main arm has been cleared are, likewise, the same as the corresponding circuits in Fig. 1, except that the automatic release circuit controlled by relay E includes a back contact 34^a of a relay J, in place of the contact 34 of Fig. 1. The calling-on arm 5 of signal S is controlled jointly by lever L and by the relay J. 115

The relay J is provided with a pick-up circuit which passes from terminal B⁵ of a 120 suitable source of current, through contact 62 on lever L, wire 57, winding of relay J, wires 58 and 59, and a normally open push button P', to terminal O⁵ of the same source of current. Contact 62 is closed from the 125 left hand indicating position to the extreme left hand position of lever L. Push button P' is in this instance not interlocked with the lever L in any way. Relay J is provided with a holding circuit which passes 130

from terminal B³, through contact 62, wire 57, winding of relay J, wires 58 and 60, and contact 61 of relay J, to terminal O⁶ of the same source of current. It follows, therefore, that when relay J is once energized, it will remain energized until lever L is returned to the normal position.

The circuit for the calling-on arm 5 passes from terminal B⁷ of a suitable source of current, through contact 47 on lever L, wire 63, contact 45^a of relay J, wire 48, contact 49, wire 50, operating mechanism of signal arm 5, and wire 24 to terminal O' of the same source of current. This calling-on arm can be cleared, therefore, when relay J is energized and lever L is in the extreme left hand position. After the calling-on arm is thus cleared it may be returned to the stop position by returning lever L to the left hand indicating position, but the lever cannot be restored to its full normal position after a train has accepted signal S' except by operation of the slow-acting hand release F. The important feature of the apparatus shown in Fig. 2 is that when the calling-on arm 5 has been cleared, the automatic release circuit controlled by relay E is ineffective owing to the fact that contact 34^a is open, so that the presence of a preceding train in block A—H does not permit lever L to be returned to the normal position.

Although I have herein described only two forms of apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a block, a signal governing traffic into said block and having a main arm and a calling-on arm, a manually operable lever for controlling said signal and having a normal position in which both of said arms indicate stop, means controlled by said lever when moved to an operated position for clearing said main arm, a lock for preventing return of said lever to normal position, approach locking means for releasing said lock except when there is a train approaching said block and automatic means for releasing said lock when a train has entered said block, an auxiliary manually controlled device having a normal position and acting to clear said calling-on arm when the device and the lever are both in operated positions, and means for preventing return of said device to normal position until the lever has been restored to normal position; characterized by the combination therewith of means associated with said auxiliary device and functioning when the device is in operated position to prevent re-
2. Railway traffic controlling apparatus comprising a block, a signal governing traffic into said block and having a main arm and a calling-on arm, a manually operable lever for controlling said signal and having a normal position in which both of said arms indicate stop, means controlled by said lever when moved to an operated position for clearing said main arm, a lock for preventing return of said lever to normal position, approach locking means for releasing said lock except when there is a train approaching said block and automatic means for releasing said lock when a train has entered said block, an auxiliary manually controlled device having a normal position and movable to an operated position when said lever is in the operated position, means for clearing said calling-on arm when said lever and said device are both in operated position, and means for preventing return of said device to normal position until the lever has been restored to normal position; characterized by the combination therewith of means associated with said auxiliary device and functioning when the device is in operated position to prevent release of said lever lock by said automatic means.
3. Railway traffic controlling apparatus comprising a block, a signal governing traffic into said block and having a main arm and a calling-on arm, a manually operable lever for controlling said signal and having a normal position in which both of said arms indicate stop, means controlled by said lever when moved to an operated position for clearing said main arm, a lock for preventing return of said lever to normal position, approach locking means for releasing said lock except when there is a train approaching said block and automatic means for releasing said lock when a train has entered said block, an auxiliary manually controlled device comprising a contact and having a normal position in which said contact is open, said device being movable to an operated position in which said contact is closed when the lever is in operated position, means for preventing return of said device to normal position until the lever has been restored to normal position, and means for clearing said calling-on arm when said lever is in operated position and said contact is closed; characterized by the combination therewith of a second contact actuated by said auxiliary device and functioning when the device is in operated position to prevent release of said lever lock by said automatic means.
4. Railway traffic controlling apparatus comprising a block, a signal governing traffic into said block and having a main

arm and a calling-on arm, a manually operable lever for controlling said signal and having a normal position in which both of said arms indicate stop, means controlled by 5 said lever when moved to an operated position for clearing said main arm, a lock for preventing return of said lever to normal position, approach locking means for releasing said lock except when there is a 10 train approaching said block and automatic means for releasing said lock when a train has entered said block, a normally open

relay, means for closing said relay when said lever is in operated position and for subsequently keeping the relay closed until 15 the lever is restored to normal position, means for clearing said calling-on arm when said relay is closed and said lever is in operated position, and means for preventing release of said lever lock by said automatic 20 means when said relay is closed.

In testimony whereof I affix my signature.

RONALD A. McCANN.
